(57) **CLAIM**

The ornamental design for a bottle, as shown and described.

DESCRIPTION

FIG. 1 is a perspective view of my new design for a bottle;
 FIG. 2 is a front view thereof;
 FIG. 3 is a rear view thereof;
 FIG. 4 is a left view thereof;
 FIG. 5 is a right view thereof;
 FIG. 6 is a top plan view thereof;
 FIG. 7 is a bottom plan view thereof; and,
 FIG. 8 is a cutaway view for 8-8 in FIG. 6 thereof.
 The broken lines in the drawings form no part of the claimed
 design.

1 Claim, 8 Drawing Sheets(56)
